ROLLER RAKE HEAD

Henry K. Stromberg, Chicago, Ill., assignor of one-half
to Frank J. Glacy, Chicago, Ill.

Application January 26, 1954, Serial No. 28,675

Term of patent 14 years

(Cl. D35—2)

To all whom it may concern:

Be it known that I, Henry K. Stromberg, a citizen of the United States, residing at Chicago, in the county of Cook and State of Illinois, have invented a new, original, and ornamental Design for a Roller Rake Head, of which the following is a specification, reference being had to the accompanying drawing, forming a part thereof.

Fig. 1 is a perspective view of a roller rake head in operative position, showing my new design;

Fig. 2 is a front elevational view;

Fig. 3 is a fragmentary top plan view showing the left end and center as illustrated in Fig. 2;

Fig. 4 is an end elevational view and may be considered as being taken from the left end of Figs. 2 and 3, showing the roller rake head in operative position; and

Fig. 5 is a cross-sectional view taken substantially

along the line 5—5 of Fig. 2, looking in the direction of the arrows, and showing the head in the position of Fig. 4.

I claim:

The ornamental design for a roller rake head, substantially as shown.
